REINFORCED-CONCRETE BEAM

Alberto Bellini, Bergamo, Italy, assignor to
Impresa A. Bellini C. S.p.A.

Filed July 21, 1965, Ser. No. 86,242

Term of patent 14 years

(Cl. D13—1)

FIG. 1 is a front elevational view of a reinforced concrete beam embodying my new design;

FIG. 2 is a partial front elevational view thereof in an enlarged scale;

FIG. 3 is a plan view of FIG. 2;

FIG. 4 is a view taken from below of FIG. 2;

FIG. 5 is a sectional view taken along the line 5—5 of FIG. 2, in a further enlarged scale;

FIG. 6 is an end elevational view of FIG. 2 in a further enlarged scale.

The essential features of the design reside in the inverted Y cross-sectional shape of the beam in combination with its variable height.

I claim:

The ornamental design for a reinforced-concrete beam, substantially as shown and described.
